WITNESS:

UNITED STATES PATENT OFFICE.

FRANK X. RATKOVIC, OF ETNA, PENNSYLVANIA.

COMBINATION TABLE AND LADDER.

1,408,398.

Specification of Letters Patent. Patented Feb. 28, 1922.

Application filed January 24, 1921. Serial No. 439,549.

To all whom it may concern:

Be it known that I, FRANK X. RATKOVIC, a citizen of the United States, residing at Etna, in the county of Allegheny and State 5 of Pennsylvania, have invented new and useful Improvements in Combination Tables and Ladders, of which the following is a specification.

This invention relates to combination furniture, and more particularly to a combination table and ladder.

One of the main objects of the invention is to provide a combination table and ladder which, in normal condition, presents a neat 15 appearance and is well adapted for use as a table. A further object is to provide a piece of furniture of the character stated which, when extended, provides a ladder which is effectively braced and possesses the 20 desired strength and rigidity. Another object is to provide a combination table and ladder of simple construction and operation which may be readily converted into either a table or ladder, as desired. Further 25 objects will appear from the detailed description.

In the drawings:

Figure 1 is a top plan view of a combination table and ladder constructed in accordance 30 with my invention.

Figure 2 is a sectional view taken substantially on line 2-2 of Figure 1.

Figure 3 is a fragmentary detail partly 35 in section showing the means for supporting one of the end boards of the table frame.

Figure 4 is a side view showing the ladder extended.

Figure 5 is an end view showing the ladder in front elevation.

40 In constructing the combination table and ladder I provide a suitable frame 1 consisting of legs 2 which are permanently connected at their upper ends by side boards 3 and an end board 4. The other end board 45 5 of the table is supported by arms 6 which are pivoted at 7 to legs 2 so as to permit the end board 5 to be swung downwardly. Each of arms 6 is provided in its inner edge with two spaced slots 8 the upper one 50 of which is adapted to engage about a headed screw 9 secured in table leg 2 so as to hold end board 5 in raised position.

A top plate 10 is normally supported by the end and side boards, and two supplemental plates 11 are mounted in each side 55 of the main plate 10. A lower ladder sec-

tion 12 is secured to the under face of plate 10 and extends substantially the full distance between end boards 4 and 5. An upper ladder section 13 is hinged at one end, at 60 14 to section 12, the hinge being positioned adjacent to end board 5. Section 12 is pivoted by means of screws 15 passed through stringers 16 to side boards 3 so as to turn about a horizontal axis extending transversely of the table. A gravity latch 17 is pivoted on one of the stringers 18 of upper ladder section 13 and is adapted, when the ladder is folded, to engage over a stud 19 secured to stringer 16 of section 12 thus 70 holding section 13 in raised or folded position. A brace bar 20 is hinged at 21 to the other end of lower section 13, and is provided at its free end with two spaced plates 22 adapted to engage about a reduced 75 portion 4^a of end board 4 when the ladder is extended, as in Figure 4.

When the ladder is folded as in Figure 2 sections 12 and 13 fit snugly together and are positioned within the end and side boards 80 so as not to be visible, brace bar 20 being supported in raised position by a cross bar 23 secured to the side boards 3. Downward movement of plate 10 when in normal position is prevented by angle brackets 24 secured to the plate and fitting into recesses 85 formed in the supplemental plates 11.

When it is desired to use the ladder, plate 10 is turned upwardly and outwardly about pivot members 15, the end board 5 being 90 first swung downwardly from beneath the end of the plate. When this is done the end of plate 10 remote from hinge 14 rests upon the supporting surface or floor, at which time latch 17 is moved by gravity out of engagement with pin or stud 19. The upper ladder section 13 is then turned so as to extend from the upper end of section 12 in substantial alignment therewith, as in Figure 4, after which the brace bar 20 is positioned so 95 that the plates 22 engage about the reduced portion 4^a of end board 4, this bar serving to effectively support the upper end of section 13. As will be noted more clearly from Figure 4, the upper end of lower section 12 100 is positioned an appreciable distance from the upper end of plate 10 and serves to brace the lower end portion of upper section 13. Also, as will be noted from Figure 4, when lower section 12 is in operative position the 105 brackets 24 engage into the lower notches 8 in arms 6 thus locking the lower portion

of section 12 against upward movement. When it is desired to convert the article into a table, upper section 13 and brace bar 20 are folded together and then turned downwardly onto lower section 12, latch 17 being moved into engagement over stud 19, after which end board 5 is raised upwardly and inwardly to release brackets 24 and the top plate with the ladder sections and associated parts is then turned upwardly and inwardly about pivots 15 into normal position these parts assuming the relative positions illustrated in Figure 2. As will be noted more clearly from Figure 2, the flights 25 of ladder section 12 extend downwardly beyond the stringers 16, and flights 25 of section 13 project upwardly beyond stringers 18 and are so positioned as to fit between the flights of the lower section. By arranging the flights in this manner it is possible to have flights of appreciable width while also permitting folding together of the ladder sections so as to occupy a minimum of space and be positioned within the end and side boards of the table frame, the table when thus folded presented a neat appearance. Also, if desired though not necessarily, a strip 27 is secured to the inner face of end board 4 and serves to support the ladder sections so as to relieve plate 10 of unnecessary strain.

An article of furniture constructed in the manner illustrated and described provides a table of neat appearance and great strength and a ladder which may be readily extended and is effectively braced for use. As will be understood, slight changes in details of construction and arrangement of parts of the invention may be resorted to without departing from the field and scope of the same, and I intend to include all such variations, as fall within the scope of the appended claims, in this application in which a preferred form only of my invention is disclosed.

What I claim is:—

1. In combination with a table including a frame and a top plate, a lower ladder section permanently secured to the under face of said plate in substantial parallelism therewith and pivoted to the frame for turning movement about an axis extending transversely of the frame, and an upper ladder section hinged to said lower section.
2. In combination with a table including a frame having side boards, and a top plate,

a lower ladder section secured to the under face of said plate and pivoted between the side boards, and an upper ladder section connected to the lower section so as to be moved into substantial parallelism therewith or into substantial alignment with said lower section, optionally.

3. In combination with a table frame having side boards and provided at one end with an end board, a top plate, a ladder section secured to the under face of said plate and pivoted between the side boards, means for preventing downward movement of the top plate when in normal position, and a second ladder section hinged at one end to the end of the first mentioned section adjacent to the other end of said frame.

4. In combination with a table frame having side boards and provided at one end with an end board, a top plate, a ladder section secured to the under face of said plate, an end board at the other end of the frame, a ladder section hinged at one end to the end of the first mentioned ladder section adjacent to the second mentioned end board, the first mentioned ladder section being pivoted between the side boards of the frame and both of said ladder sections being adapted to fit within said side and end boards, means for supporting said second mentioned end board so as to permit the same to be moved downwardly from beneath the top plate, and means carried by the top plate and cooperating with the means for supporting the second mentioned end board for securing said top plate against upward movement about its pivotal axis.

5. In combination with a table frame having side boards, a top plate, a ladder section secured to the under face of said top plate and pivoted between the side boards, a second ladder section hinged at one end to one end of the first mentioned section, the flights of the ladder sections projecting beyond the stringers and being so related that the flights of each section fit between the flights of the other section when said sections are in folded position, a brace bar hinged to the other end of the second mentioned section, means for holding said second mentioned section raised when the ladder is folded, and means for holding said brace bar raised when the ladder is folded and the top plate is in normal position.

In testimony whereof I affix my signature.
FRANK X. RATKOVIC.
